HERMAN W. BLOCK, OF NEW YORK, AND BERNARD H. CHRISTENSON, OF NORTH WHITE PLAINS, NEW YORK, ASSIGNORS TO S. STEIN & CO., OF NEW YORK, N. Y.

DISPLAY CONTAINER

Application filed July 16, 1930. Serial No. 468,386.

This invention relates to display containers for delicate high-piled fabrics and like materials.

The arrangement in display cases such as used by salesmen or for similar purposes, of high-piled fabrics such as overcoatings, made of camel's hair, or similar material, in order to be able to display such fabrics at will, or to be capable of easy transportation from one customer to another, raises many problems. It is important that the material when displayed should present substantially the appearance it will have under the most favorable circumstances; the material must be positioned within the container so as to eliminate or reduce the danger of crushing the material samples either from the weight of superposed material samples, or from the weight of containers or similar burdens piled on top of the case within which the samples are housed.

Merely to protect material samples of this type against crushing during transportation is not in itself sufficient; it is requisite that the material be retained securely within the case so that it cannot easily be separated therefrom, and further, though so secured, that it should be accessible and visible without any difficulty and that the sheets holding the material should be capable of being laid down flat so that no substantial shadows will fall on the material from the sheets themselves to detract from the appearance of the samples when on display.

It is an object of this invention to provide a container for permanently retaining and displaying high-piled crushable materials, of the type hereinabove set forth, in which the several portions of the container are so constructed as to protect such materials against crushing and permit the materials to retain their raised effect during transportation thereof so as to be ready for display at practically any time.

It is a further object of this invention to provide, in a container of the type hereinabove set forth, means for retaining material samples of the type specified which, when it is desired to display the fabrics, may be disposed entirely flat so that the fabrics may be

viewed in their entirety without the interference of shadows from bent up retaining devices and in which the individual samples are easily and conveniently accessible for examination.

It is an additional object of this invention to provide a display case for fabrics of the type hereinabove set forth, simply and economically manufactured, which permits a full and unhindered view of each and every sample contained in said case.

Other objects of this invention will be apparent from the description hereinafter, or will be specifically pointed out herein.

The invention is not intended to be restricted to the construction and arrangement of parts herein shown and described, nor to the various details thereof, as the same may be modified in various particulars without departing from the spirit and scope of the invention, one practical embodiment of which has been herein illustrated and described without attempting to show all of the various forms and modifications in which the invention might be embodied.

In the accompanying drawing, in which is shown one of the various possible illustrative embodiments of this invention,

Fig. 1 is a perspective view of a display case embodying the invention, the case being shown with the cover thereof open and portions thereof broken away.

Fig. 2 is a transverse vertical sectional view through said display case, the cover being shown closed.

In the embodiment of the invention appearing on the drawing, the display case 10 is seen to include a bottom 12 at the side edges of which rise the side walls 14. An end wall 16 has an edge thereof hingedly secured at one end to an end edge of the bottom, and has the cover 18 hingedly connected to the other edge thereof. Retained within the container are a plurality of sheets 20, preferably in the form of bound pages, for a purpose hereinafter appearing.

The bottom end wall and the flat body portion 21 of the cover are made of substantially the same material, preferably of some

light strong material such as heavy cardboard, fibre board, or the like. It is desirable that these parts have a high degree of rigidity because of the strains which it is intended these parts should resist. The side walls due, as is set forth more fully hereinafter, to the load which it is intended that they shall withstand, are made of material heavier in cross-section than that utilized for the bottom, end wall and cover. These pieces of material are secured in any suitable manner, at the extreme side edges of the bottom. A preferred method of assembly involves gluing an end face of the side wall against the top face of the bottom, the increased thickness of the wall material providing a greater gripping area for retaining the two bodies secured together.

Preferably, the side walls and the bottom are faced with a fabric 22, which is pasted thereto, and assists in retaining these members in assembled relation. The fabric 22 may be continued beyond the bottom to be used as a facing for end wall 16, being pasted around the side edges of the end wall to retain the same securely, but flexibly, and hingedly bonded with the bottom, with which it requires no other connection. Preferably, however, another fabric portion 24 may be secured to the inner face of the end wall, the ends of this fabric portion being then retained under the ends of the linings of the cover and bottom, as hereinafter appears.

The cover 18 may likewise be provided with a continuous fabric facing and lining 28, folded over the side edges of the cover, and at the end thereof adjacent the end wall, sealed over the other end of fabric portion 24. The construction in which the end wall is connected to the bottom and cover only by flexible material permits a substantial hinging action between the adjacent parts at the joints 30 and 32, provided by the free portions of the fabric, lining or facing. By this construction, when the cover is opened away from its closed position, the bottom, end wall and cover will be capable of all lying within the same plane, for a purpose hereinafter appearing.

Secured to the end wall is any desired number of groups 34 of substantially flexible sheets 20, preferably having considerable stiffness, and being, in a preferred embodiment, formed of heavy paper capable of receiving thereon samples of material as hereinafter appears. The groups are formed by round folding a number of sheets and then binding the groups to the wall by thread 38, the groups being spaced apart a sufficient distance to provide a distinct gap 40 between adjacent groups. The thread passes through the sheets and a section 41 of stiff board which is anchored flexibly in position by means of a fabric strip 43 which, together with the ends of portion 24, may be overlapped, and

held in position, by the linings 45 and 28 of the bottom and cover, respectively.

When high piled fabrics are pasted or otherwise secured to the faces of the sheets, and the sheets are then closed together, as shown in Fig. 2, the tendency, due to the substantial rigidity of the sheets, will be to protect the fabrics against compression, the sagging of the pages being counteracted sufficiently to prevent harm to the fabrics. However, due to the arrangement of the sheets upon the end wall and the relation of the cover thereto when the cover is moved to open position, the end wall will rest flat upon the same surface as the bottom and the cover and the sheets themselves may be opened out flat. The fabrics secured to the sheets are then open to view without interference from shadows thrown by the sheets themselves, as in those cases where it was necessary to hold such sheets in an upright position. The visibility of the sheet at any angle thereto is not affected, since the sheets lie flat and there are no obstructions.

Portions 42 of fabric, such as overcoatings made of camel's hair cloth, or similar delicate and/or high-piled fabrics, are secured to the faces of sheets, either by pasting a smooth face of the fabric to the sheet, or by any other suitable method. Preferably, fabric portions are not secured to opposite faces of adjacent sheets but are secured to the alternate faces so that when the cover and the sheets are closed, one upon the other, no fabric portion will be directly in abutment with another. Upon the sheet face thus left free, there may be imprinted descriptive matter concerning the portions upon the opposite face; it is also intended to attach to such face labels 44 which are to be used in the trade to distinguish such material, and which labels may have any suitable indicia, such as trademark or the like, imprinted thereon.

The cover is of such width as to have the side edges thereof, when closed, disposed upon the upper free surfaces of the side walls so that the cover is supported thereon. The bottom, adjacent the end edges of the side walls and remote from the end wall and the cover, is extended beyond the side walls to provide a ledge 46 which cooperates with a lip 48, extending downwardly from the covers. The lip is preferably formed of rigid material substantially of the same thickness as the side walls, and may have an end face thereof pasted to the face of the cover. The facing and lining of the cover is continued around the lip for additional bonding of the lip and the cover. The lip rests upon the ledge in such manner as to provide a firm additional support for the cover, retaining the same spaced relatively to material retained upon the sheets within the container. In this manner, the cover is prevented from bearing directly upon any of the fabrics retained upon

the sheets; the cover being thus supported both by the ledge and by its point of rest upon the top edges of the side walls can support the weight of other members which otherwise

5 might tend to crush the cover into the case against such materials. The case, however, still retains the property of easy accessibility to the materials therein; its construction permits opening thereof to display to the best

10 advantage materials therein contained.

As many changes could be made in the construction herein involved, and many widely different embodiments of the invention designed without departing from the scope of 15 the invention, as defined in the accompanying claims, the matter set forth by the above description may be interpreted as illustrative of an operative embodiment of the invention and not in a limiting sense.

20 What we claim is:

1. A display container for high piled or similar delicate fabrics, constructed to protect the same against crushing, which includes: a rigid frame consisting of a bottom 25 and a pair of side walls secured to and extending upwardly from said bottom, a cover, a rigid end wall for said frame hingedly connecting said cover and said bottom, said cover and end wall being of sufficient width to rest 30 upon the tops, and against the ends, respectively, of said side walls, when in closed position, and a plurality of fabric receiving members secured to said end wall to lie within said container when said cover is closed, said members having portions of said fabrics affixed thereto for display purposes, said members and said end wall being so positioned as to be substantially flat when opened away from said frame, said bottom extending 35 beyond said side walls, and said cover having a lip formed thereon, said lip, when said cover is in closed position, resting upon said bottom extension to maintain said cover in spaced relation to said members and the 40 fabric portions thereto affixed.

2. A display container for high piled or similar delicate fabrics, construction to protect the same against crushing, which includes: a rigid frame consisting of a bottom, and a pair of side walls secured to and extending upwardly from said bottom, a cover, a rigid end wall for said frame hingedly connecting said cover and said bottom, said cover and end wall being of sufficient width to rest upon the tops, and against the ends, respectively, of said side walls, when in closed position, and a plurality of fabric receiving members secured to said end wall to lie within said container when said cover is closed, said members having portions of said fabrics affixed thereto for display purposes, said members and said end wall being so positioned as to be substantially flat when opened away from said frame, said bottom extending beyond said side walls, and

said cover having a lip formed thereon, said lip, when said cover is in closed position, resting upon said bottom extension to maintain said cover in spaced relation to said members.

3. A display container for high piled, or similar delicate fabrics, constructed to protect the same against crushing, which includes: a rigid frame consisting of a bottom, and a pair of side walls secured to and extending upwardly from said bottom, a cover, a rigid end wall for said frame hingedly connecting said cover and said bottom, said cover and end wall being of sufficient width to rest upon the tops, and against the ends, respectively, of said side walls, when in closed position, and a plurality of fabric receiving members secured to said end wall to lie within said container when said cover is closed, said members having portions of said fabrics affixed thereto for display purposes, said members and said end wall being so positioned as to be substantially flat when opened away from said frame, said bottom extending beyond said side walls, and said cover having a lip formed thereon, said lip, when said cover is in closed position, resting upon said bottom extension.

4. A display container for high piled, or similar fabrics, constructed to protect the same against crushing, which includes: a rigid frame consisting of a bottom, and a pair of side walls secured to and extending upwardly from said bottom, a cover, a rigid end wall for said frame hingedly connecting said cover and said bottom, said cover and end wall being of sufficient width to rest upon the tops, and against the ends, respectively, of said side walls, when in closed position, and a plurality of fabric receiving members secured to said end wall to lie within said container when said cover is closed, said members having portions of said fabrics affixed thereto for display purposes, said members and said end wall being so positioned as to be substantially flat when opened away from said frame, said bottom extending beyond said side walls, and said cover having a lip formed thereon to cooperate therewith.

5. A display container for high piled, or similar delicate fabrics, constructed to protect the same against crushing, which includes: a rigid frame consisting of a bottom, and a pair of side walls secured to and extending upwardly from said bottom, a cover, a rigid end wall for said frame hingedly connecting said cover and said bottom, said cover and end wall being of sufficient width to rest upon the tops, and against the ends, respectively, of said side walls, when in closed position, and a plurality of fabric receiving members secured to said end wall to lie within said container when said cover is closed, said members having portions of said fabrics af-

fixed thereto for display purposes, said members and said end wall being so positioned as to be substantially flat when opened away from said frame.

5. A display container for high piled, or similar delicate fabrics, constructed to protect the same against crushing, which includes: a rigid frame consisting of a bottom, and a pair of side walls secured to and extending upwardly from said bottom, a cover, a rigid end wall for said frame hingedly connecting said cover and said bottom, said cover being of sufficient width to rest upon the tops of said side walls, when in closed position, and a plurality of fabric receiving members secured to said end wall to lie within said container when said cover is closed, said members having portions of said fabrics affixed thereto for display purposes, said members and said end wall being so positioned as to be substantially flat when opened away from said frame.

6. A display container for high piled, or similar delicate fabrics, constructed to protect the same against crushing, which includes: a rigid frame consisting of a bottom, and a pair of side walls secured to and extending upwardly from said bottom, a cover hinged at one end of said bottom and of sufficient width to rest upon the tops of said walls, when in closed position, and a plurality of fabric receiving members secured in said container between said frame and said cover, said members having portions of said fabrics affixed thereto for display purposes, and being so positioned as to be substantially flat when opened away from said frame, said bottom extending beyond said side walls, and said cover having a lip formed thereon, said lip, when said cover is in closed position, resting upon said bottom extension to maintain said cover in spaced relation to said members and the fabric portions thereto affixed.

7. A display container for high piled or similar delicate fabrics, constructed to protect the same against crushing, which includes: a rigid frame consisting of a bottom, and a pair of side walls secured to and extending upwardly from said bottom, a cover hinged at one end of said bottom and of sufficient width to rest upon the tops of said side walls, when in closed position, and a plurality of fabric receiving members secured in said container between said frame and said cover, said members having portions of said fabrics affixed thereto for display purposes, and being so positioned as to be substantially flat when said cover is opened away from said frame, said bottom extending beyond said side walls, and said cover having a lip formed thereon, said lip, when in closed position, resting upon said bottom extension to maintain said cover in spaced relation to said members.

8. A display container for high piled or

similar delicate fabrics, constructed to protect the same against crushing which includes: a rigid frame consisting of a bottom, and a pair of side walls secured to and extending upwardly from said bottom, a cover hinged at one end of said bottom and of sufficient width to rest upon the tops of said side walls, when in closed position, and a plurality of fabric receiving members secured in said container between said frame and said cover, said members being so positioned as to be substantially flat when opened away from said frame, said bottom extending beyond said side walls, and said cover having a lip formed thereon, said lip when said cover is in closed position resting upon said bottom extension to maintain said cover in spaced relation to said members.

9. A display container for high piled or similar delicate fabrics, constructed to protect the same against crushing, which includes: a rigid frame consisting of a bottom and a pair of side walls secured to and extending upwardly from said bottom, a cover hinged at one end of said bottom and of sufficient width to rest upon the tops of said side walls, when in closed position, and a plurality of fabric receiving members secured in said container between said frame and said cover, said members being so positioned as to be substantially flat when opened away from said frame, said bottom extending beyond said side walls, and said cover having a lip formed thereon, said lip, when said cover is in closed position, resting upon said bottom extension.

10. A display container for high-piled or similar delicate fabrics, constructed to protect the same against crushing which includes: a rigid frame consisting of a bottom and a pair of side walls secured to and extending upwardly from said bottom, a cover hinged at one end of said bottom and of sufficient width to rest upon the tops of said side walls, when in closed position, and a plurality of fabric receiving members secured in said container between said frame and said cover, said members being so positioned as to be substantially flat when opened away from said frame, said bottom extending beyond said side walls, and said cover having a lip formed thereon, said lip, when said cover is in closed position, resting upon said bottom extension.

11. A display container for high piled or similar delicate fabrics, constructed to protect the same against crushing, which includes: a rigid frame consisting of a bottom and a pair of side walls secured to and extending upwardly from said bottom, a cover hinged at one end of said bottom and of sufficient width to rest upon the tops of said side walls, when in closed position, and a plurality of fabric receiving members secured in said container between said frame and said cover, said members being so positioned as to be substantially flat when opened away from said frame, said bottom extending beyond said side walls, and said cover having a lip formed thereon to cooperate with said extension.

12. A display container for high piled or

for display purposes, said members and said end wall being so positioned as to be substantially flat when opened away from said frame.

5 13. A display container for high piled or similar delicate fabrics, constructed to protect the same against crushing, which includes: a rigid frame consisting of a bottom and a pair of side walls secured to and extending upwardly from said bottom, a cover, a rigid end wall for said frame hingedly connecting said cover and said bottom, and a plurality of fabric receiving members secured to said end wall to lie within said container when said cover is closed, said members having portions of said fabrics affixed thereto for display purposes, and being so positioned as to be substantially flat when opened away from said frame.

10 14. A display container for high piled or similar delicate fabrics, constructed to protect the same against crushing, which includes: a rigid frame consisting of a bottom and a pair of side walls secured to and extending upwardly from said bottom, a cover, a rigid end wall for said frame hingedly connecting said cover and said bottom, and a plurality of fabric receiving members secured in said container between said frame and said cover, said members having portions of said fabrics affixed thereto for display purposes, and being so positioned as to be substantially flat when opened away from said frame.

15 15. A display container for high piled or similar delicate fabrics, constructed to protect the same against crushing, which includes: a rigid frame consisting of a bottom, and a pair of side walls secured to and extending upwardly from said bottom, a cover hinged at one end of said bottom and of sufficient width to rest upon the tops of said side walls, when in closed position, and a plurality of fabric receiving members secured in said container between said frame and said cover, said members being so positioned as to be substantially flat when opened away from said frame.

20 16. A display container for high piled or similar delicate fabrics, constructed to protect the same against crushing, which includes: a rigid frame consisting of a bottom and a pair of side walls secured to and extending upwardly from said bottom, a cover hinged at one end of said bottom, and a plurality of fabric receiving members, consisting of folded sheets secured, at the folds, in said container between said frame and said cover, said members being so positioned as to be substantially flat when opened away from said frame.

25 17. A display container for high piled or similar delicate fabrics, constructed to protect the same against crushing, which includes: a rigid frame consisting of a bottom,

and a pair of side walls secured to and extending upwardly from said bottom, a hinged cover for said frame, and a plurality of fabric receiving members, consisting of folded sheets secured, at the folds, in said container between said frame and said cover, said members being so positioned as to be substantially flat when opened away from said frame.

30 18. A display container for high piled or similar fabrics, constructed to protect the same against crushing, which includes: a rigid frame open at the top thereof, a hinged cover for said frame, and a plurality of fabric receiving members, consisting of folded sheets secured, at the folds, in said container between said frame and said cover, said members having portions of said fabrics affixed thereto for display purposes and being so positioned as to be substantially flat when opened away from said frame.

35 19. A display container for high piled or similar fabrics, constructed to protect the same against crushing, which includes: a rigid frame open at the top thereof, a hinged cover for said frame, and a plurality of fabric receiving members, consisting of folded sheets secured, at the folds, in said container between said frame and said cover, said members being so positioned as to be substantially flat when opened away from said frame.

In testimony whereof they have affixed their signatures.
